TOY GUN

William C. Peterson, 31 Water St., Claremont, N.H.

Filed Feb. 26, 1963, Ser. No. 73,730

Term of patent 7 years

(Cl. D34—15)

FIG. 1 is a top plan view of a toy gun, showing my new design; and

FIG. 2 is a side elevational view, the opposite being substantially the same.

I claim:

The ornamental design for a toy gun, as shown and described.
